DWELLING HEATER INSTALLATION

Filed Oct. 10, 1927

Inventor

Frank A. Howard

By his Attorney *Att. Strawn*

UNITED STATES PATENT OFFICE

FRANK A. HOWARD, OF ELIZABETH, NEW JERSEY, ASSIGNOR TO STANDARD OIL DEVELOPMENT COMPANY, A CORPORATION OF DELAWARE

DWELLING HEATER INSTALLATION

Application filed October 10, 1927. Serial No. 225,183.

This invention relates to dwelling heater installations utilizing liquid fuels and comprehends broadly the combination of a burner for liquid fuels, a means for compressing gas operated in conjunction therewith, a reservoir for liquid fuel and an air lift to transfer fuel from said reservoir to a smaller receptacle from which the burner is directly supplied.

10 The drawing is a diagrammatic vertical cross section of a preferred embodiment of my invention, in which

The dwelling heater 1 may be of any type such as a steam boiler, hot water heater, or 15 hot air heater. It is heated by the burner 2 controlled by any suitable mechanism indicated by 3. Air or other gas is compressed by the compressor 5 actuated by motor 4. The term gas will be herein employed to denote 20 air or any other material gaseous at ordinary temperature. Preferably burner 2 operates through the atomization of a liquid fuel by means of a compressed gas such as air or recycled flue gas; the motor and compressor are 25 preferably designed for this purpose and operate when gas is required for atomization. If the motor and compressor are not required for this purpose, they may, nevertheless, be adapted to operate simultaneously 30 with the burner.

A supply of fuel for the burner is retained in the storage tank 6, preferably underground, which may be refilled by means of pipe 7 terminating at the ground level and 35 sealed by the vented removable plug 8. The liquid hydrocarbon fuel flows from 6 through pipe 9 into the sump 10 covered by plate 11. The storage tank 6 and sump 10 form together the source of oil supply for the receptacle 18 situated at the higher level. The 40 pipe 12 projects downwardly into this sump and at the other end discharges into the receptacle 18. Compressed gas required for the operation of the burner is carried to control mechanism 3 by means of pipe 13 controlled by valve 14. A part of the gas is diverted by means of pipe 15 controlled by valve 16. This pipe is provided with bend 17 or equivalent device such as a check valve to 45 prevent the flow of fuel by gravity into the

compressor when not in operation. If the motor and compressor are not required for the operation of the burner but are adapted to operate simultaneously therewith, the pipe 13 may be dispensed with and sealed off. 55

The pipe 15 discharges the compressed gas into pipe 12 in sump 10 or into such relationship thereto that a mixed column of gas and oil is formed in pipe 12 of lesser hydrostatic head than the column of oil in the sump, 60 thereby causing a transfer of oil to the receptacle 18. The pipe 12 terminates within the receptacle 18 in the float operated shutoff valve 19 whereby the amount of oil introduced may be restricted to that necessary to 65 maintain a definite level in 18. Gas entering with the oil may be vented through the pipe 19 controlled by valve 20. The float operated shutoff valve may be dispensed with in which event any excess of oil over that necessary to maintain the desired level in 18 returns through pipe 21 controlled by valve 22 70 communicating with the reservoir. The pipe 23 controlled by valve 24 connects with the receptacle 18 at or near the lower part thereof and conducts liquid fuel by gravity to the burner control mechanism 3 by which it is supplied to the burner 2. 75

It will be understood that the equipment shown is in illustration and not in limitation and that various alternatives may be adopted within the scope of the appended claims in which it is my intention to claim broadly all novelty inherent in the invention. 80

I claim:

1. An oil supply system for oil burners comprising a source of oil supply, a receptacle at a level above the source of supply a delivery pipe extending into the source of supply adjacent the bottom thereof and communicating with the receptacle, a source for supplying gas under pressure, means for discharging gas from the source of gas to the delivery pipe adjacent the lower end thereof and beneath the level of oil in said oil supply source, whereby a mixed column of gas and oil is formed in the delivery pipe of lesser hydrostatic head than the column of oil in the oil supply source and the oil is caused to flow to the receptacle, and a pipe to conduct oil 90

by gravity from the receptacle to the burner.

2. Apparatus according to claim 1 in which the source of oil supply comprises an oil reservoir a sump into which the delivery pipe extends, and means allowing the passage of oil from the reservoir into the sump.

3. Apparatus according to claim 1 in which the receptacle is provided with a vent pipe.

4. Apparatus according to claim 1 in which a pipe connection is provided to allow the return of surplus air and oil from the receptacle to the source of oil supply above the oil level therein.

5. Apparatus according to claim 1 in which a float operated valve is provided in said receptacle to control the fuel introduced in relation to the level of fuel therein.
